UNITED STATES PATENT OFFICE

VERNON S. BECK, OF WINFIELD, KANSAS

GAS BURNER

Application filed October 30, 1929. Serial No. 403,615.

- My invention relates to an improvement in gas burners.
- The principal object of my invention is to provide a gas burner insertible into a cast frame that is stationarily supported by the masonry of the furnace, by which means the burner may be removed for repairs, or to replace deteriorated refractory members, the removal of the burner not interfering with, or damaging, the structure supporting the same.
- The further object of my invention is to provide a standard fire brick refractory element supported by the inner portions of the burner, said refractory elements being in parts, of stock dimensions, and removeably arranged, so that a defective portion may be replaced.
- A still further object of my invention is to provide a burner having a primary supply of air to enter with the gas flow, and a secondary air supply passing through openings between the tubes comprising the burner and coming in contact with the combustion at the burner tube ends, by which means overheating of the burner tubes is prevented.
- A still further object of my invention is to provide a baffle means to control the secondary air supply through the medium of the refractory elements positioned between the burner tubes.
- A still further object of my invention is to provide a rectangular jamb element of a certain depth, and, in case the masonry of the wall is of a greater depth than the width of the jamb the box-like structure in which the burner is positioned, will function as an extension for the jamb so that the combustion ends of the burner will extend past the inside surface of the wall, by which means the burner is adjustable to walls of different thickness.
- These and other objects will hereinafter be more fully explained, reference being had to accompanying drawings forming a part of this specification, in which like characters apply to like parts in the different views.
- Referring to the drawings, Fig. 1 is a sectional view along line 1-1 in Fig. 4, looking in the direction of the arrows. Fig. 2 is an inside view of the burner. Fig. 3 is a front view of the burner, showing the manifold, with respect to the burner tubes. Fig. 4 is an elevation showing the installation of the burner and the door enclosing the same, the burner manifold being shown by dotted lines.
- My invention herein disclosed consists of a jamb 1, said jamb being securely fastened to furnace wall 2, fragmentarily shown.
- Positioned within the jamb is a box-like structure 3, functioning as an extension for the jamb, as an adjustment for walls of different thickness. Note that the box and the jamb referred to are connected by means of bolts B positioned at each corner respectively, by which means the box element is rigidly positioned with respect to the width of the furnace wall. Positioned within said box is a burner element consisting of a plurality of funnelled tubes 4, said tubes being in parallelism and integrally connected at the outer ends, the inner ends being spaced apart, and having fire clay brick 5, of stock dimensions, placed horizontally therebetween, said brick loosely engaging and adapted to slide inward or outward longitudinally of the tubes, by which means the point of combustion may be spaced from the inner or nozzle ends of the metal tubes, tending to eliminate excess heating of the tubes. I have also placed a line of fire clay brick between the outer sides of the tubing and the box, said brick also capable of sliding longitudinally with respect to the tubes to the same alignment of the first said brick, by which means the adjacent edge of the box is protected from the combustion.
- The tubes of the burner are slightly funnelled at the outer side thereof, as a means of freely receiving the gas and primary air supply which enters the tube, said tube functioning as a mixing chamber. Positioned between the separate tubes are openings 6 providing a secondary supply of air, for combustion and also for cooling the tubes.
- These openings may be controlled in size by moving the refractory elements 5 inward or outward with reference to the tubing.
- Should the combustion tend to heat the

adjacent ends of the tubes, aforesaid brick may be moved outward away from the tube ends, as heretofore described, and simultaneously permit an increased flow of the 5 secondary air supply, coacting as a further cooling means.

Extending downward from the assembled tubes are lugs 7, and outward from the sides lugs 8, as a spacing means for the 10 tubed element from the walls of the box. Securely attached to the tubed element is a manifold consisting of a plurality of winged members 9 positioned in horizontal parallelism and connected by a neck member 10, said 15 neck and wing members being hollow, thereby functioning as a gas chamber.

Positioned on the side of the wing members adjacent the tube element is a plurality of jets 11, outwardly extending and 20 being spaced apart to axially align with their respective tubes, by which means the gas is injected through all of the tubes simultaneously.

As a means of connecting the manifold 25 to the tube element I have placed a bolt 12 near each corner, said bolt having a sleeve element 13 thereon, which acts as a spacing means between the manifold and the tube element, said bolts being secured by nuts 30 14 threadedly engaging thereon. On the lower wing of the manifold is a hub 15, outwardly extending, and threaded to receive a gas supply pipe 16, said pipe having a valve control not shown in the drawings.

35 Hingedly connected to jamb 1 is a door 17 having an elongated slot A positioned therein, into which the supply pipe will engage when the door is closed. As a means of supporting the door in the desired open 40 position a notched sector 18 pivoted on the jamb, is adapted to engage with a detent 19 on the door, by which means the air supply for the burner is controlled. While I have shown and described a single unit 45 as a burner, other units may be adjoined, by which means a battery of burners may be installed, and such other modifications may be employed as lie within the scope of the appended claims; and having fully 50 described my invention, what I claim as new and desire to secure by Letters Patent is:

1. In a gas burner; a plurality of burner tubes, integrally connected, the tubes having spaces therebetween for a secondary air supply externally thereof; a frame in which the tube structure is positioned and means for 55 spacing the combustion point from the inner ends of the tubes; a manifold comprising a plurality of hollow wings, a plurality of 60 jets projecting from each of the wings as a means for injecting gas through each of the tubes simultaneously, the manifold being attached to the outer portion of the tube structure, and means for rigidly attaching 65 and spacing the manifold.

2. A burner of the class described comprising; a plurality of funnelled tubes in alignment horizontally and perpendicularly, being integrally connected at the funnelled ends, the opposite ends being spaced apart 70 horizontally, and fire clay brick being positioned between and around the tube structure; a frame as supporting means therefor and loosely engaging therewith; a winged manifold, the wings having a plurality of 75 jets, the wings being connected by a neck and laterally extending from each side thereof, and means for connecting the manifold to the tube structure so that each of the jets will be in axial alignment with the 80 tubes respectively; and means of supplying the burner with gas.

3. A burner of the class described comprising; a plurality of funnelled tubes, each tube being a mixing chamber; means for 85 introducing an air supply between the tubes as an additional air supply at the combustion point and as a cooling means for the tubes; a rectangular frame, and lug extensions on the tube structure as spacing means 90 for centrally positioning tube structure within the frame; fire clay brick positioned between the horizontal rows of tubes and adapted to extend outward from the ends of the tubes; and a manifold having a supply pipe connected thereto, the manifold arranged to inject gas into each of the tubes 95 simultaneously.

4. A burner comprising a jetted manifold, and means for supplying gas thereto; a 100 structure comprising a plurality of funnelled tubes positioned in rows horizontally and perpendicularly, being integrally connected at the funnelled ends, and having openings therebetween as air circulating 105 means between the tubes, the tubes being axially aligned with their respective jets on the manifold, the manifold being connected in close proximity to the funnelled ends of the tubes; fireproof elements positioned between the horizontal rows of tubes and projecting outward therefrom as spacing means for the gas mixture from the ends of the tubes, and fireproof elements extending 110 around the outside of tubes, and a frame to receive the assembled parts specified, the frame functioning as an extension jamb in 115 a furnace wall; and a jamb having a door and means of adjusting the door in an open position as an air controlling means for the burner.

5. In a gas burner; a door jamb element and a box-like element to function as a jamb, and means for connecting the jamb and box elements, so that the outer edge of 125 each may be set flush with their respective sides of a wall; a gas burner consisting of a manifold, with a plurality of jets spaced apart and a mixing chamber comprising a plurality of tubular members; means for 130

connecting the tubular members in working relation to the manifold; fire clay brick insulating the tubular members from the sides of the box, and separating the inner ends of 5 the horizontal rows of tubes; a door hingedly connected to the upper side of the jamb member, the door having a slot in the lower side, through which the supply pipe of the manifold extends, the door being detained 10 by a notched sector pivotally engaging on the jamb, all as and for the purpose specified.

6. In a burner of the character described, in combination with a furnace including a 15 wall having a door opening, a frame mounted in said opening having an outer end spaced from the outer end of the opening, a plurality of tubes removably mounted in said frame, means for delivering fuel to said 20 tubes, and a jamb member fixed in the outer end of said opening and connected with the frame.

7. In a gas burner, a manifold comprising a plurality of hollow wings extending in 25 opposite directions from a centrally disposed hollow column, each wing having a plurality of jets from which gas will eject simultaneously, the column of the manifold being connected to a supply pipe, tubes 30 forming a mixing chamber for each of the jets, and means for accurate alignment of the tubes with the jets, the tubes being spaced apart vertically as a means for receiving fire clay brick for the purpose specified, and a jamb element to support the 35 mixing chamber structure, the mixing chamber removably arranged.

In testimony whereof I affix my signature.
